UNITED STATES PATENT OFFICE.

JOHN L. ADAMS, OF CHICAGO, ILLINOIS.

NURSE'S PORTABLE STERILIZING OUTFIT.

Application filed August 27, 1927. Serial No. 215,849.

This invention relates to certain novel improvements in nurses' portable sterilizing outfits and has for its principal object the provision of an improved construction of this character which will be highly efficient in use and economical in manufacture.

Among the several objects of the invention is to provide a kit of the class herein-after more fully set forth which is constructed to accommodate small pans or cups for sterilizing hypodermic needles and other medical tools and also which kit has sufficient room for the storage of hypodermic needles, medical thermometers, and the like.

15 Other objects will appear hereinafter.

The invention consists in the novel combination and arrangement of parts to be hereinafter described and claimed.

The invention will be best understood by 20 reference to the accompanying drawings, showing the preferred form of construction and in which:

Fig. 1 is a plan view of the invention in open position;

25 Fig. 2 is a sectional detail view taken substantially on line 2—2 of Fig. 1 showing certain pans or cups in operative position; and

Fig. 3 is a sectional detail view taken substantially on line 3—3 of Fig. 1.

30 Referring more particularly to the drawing, 10 and 11 indicate a cover and bottom respectively. This cover and bottom 10 and 11 have their adjacent edge portions 12 hingedly connected together by means of 35 hinges 13. When the cover 10 is in closing position with respect to the bottom 11, the cover is releasably attached to the bottom 11 through the medium of a latch structure 14. The cover 10 has on its top wall 15 a

40 plurality of spaced spring clips 16 which clips function to detachably hold within the cover a nurse's articles such as hypodermic needles, thermometers and the like. A tray 45 is indicated at 17 and this tray is adapted to be mounted in the bottom 11. Secured to the wall 18 of the tray is a plate 19 providing

50 knuckles 20. A leg is indicated at 21 and this leg has one end portion providing a knuckle 22 which is adapted to be dis-

55 posed between the knuckles 20 of the plate 19 and the knuckle 22 and knuckles 20 are secured together through the medium of a pin 23. The opposite end portion of the legs provides a knuckle 24 which fits between

knuckles 25 provided by one end portion of an extension 26. This extension 26 is formed as an integral part of a cup 27.

Secured to the wall 18 of the tray 17 is a plate 28 disposed at right angles with respect to the plate 19 and this plate 28 provides a knuckle 29 which fits between knuckles 30 provided by an extension 31 formed as an integral part of a cup 32. The plate 28 and extension 31 are arranged so as to dispose the cup 32 beneath the cup 27

when the extension 26 and leg 21 are disposed flat upon the wall 18 in aligned position with respect to each other. Outwardly of the plate 19 there is secured to the wall 18 a plate 33 providing a knuckle 34 which

fits between knuckles 35 provided by a leg 36. The leg 36 provides knuckles 37 which are disposed on opposite sides of a knuckle 38 provided by an extension 39 formed as an integral part of a cup 40. The knuckles 35 and 34 and 37 and 38 are connected together by means of pins 41. The cup 40 is disposed over a smaller cup 41 providing an extension 42 having formed on its outer end portion a knuckle 43. This knuckle 43 fits

50 between knuckles 44 and the knuckles are connected together by means of a pin 45. The knuckles 44 are formed as an integral part of a plate 46 secured to the wall 18. When the extended portion 39 and leg 36 are flatly positioned to dispose the cup 40 over the cup 41 and in aligned position with respect to each other, the cup 40 will be disposed in a direction opposite to the disposition of the cup 27 within the cover 17. Between the plates 21 and 36 there is secured to the wall 18 a finger ring 47 which facilitates removing the tray from within the cover.

55 In use, the cups 27 and 40 are adapted to be used for sterilizing hypodermic needles or the like and to accomplish this the device is put into operation as follows. The cup 27, when confined in the cover, will be in an inverted position over the cup 32 which is likewise in an inverted position. To use the cup 27 the plate 21 is pivoted upwardly about the pin 32 to dispose the plate 21 in a substantially vertical position. The extension 26 is pivoted about the pin 26 which connects the knuckles 21 and 24 in a position substantially at right angles with respect to the plate 21 whereby to support the cup 27 in a horizontal plane as best shown in Fig. 1. Prior to the disposition

110

of the cup in this position the cup 41 is pivoted about the pin 44 to dispose this cup in a position beneath the cup 27. Alcohol is then poured into the cup 41 and ignited 5 when this cup 41 is beneath the cup 27 whereby to boil water confined in the cup 27 for sterilizing hypodermic needles or the like. The cup 40 is swung upwardly in a position to be supported in a horizontal 10 plane by the leg 36 as best shown in Fig. 2, over the cup 32 which is swung upwardly to be disposed beneath the cup 40, said cup 32 likewise being adapted to receive an inflammable liquid such as alcohol for boiling 15 water within the cup 40. By the use of the kit as herein set forth it is obvious that hypodermic needles and other medical tools may be thoroughly sterilized without coming in contact with the hand.

20 While I have illustrated and described the preferred form of construction for carrying my invention into effect, this is capable of variation and modification, without departing from the spirit of the invention. I, 25 therefore, do not wish to be limited to the precise details of construction set forth, but desire to avail myself of such variations and modifications as come within the scope of the appended claims.

30 Having thus described my invention what I claim as new and desire to protect by Letters Patent is:

1. In a nurse's portable sterilizing kit, a 35 casing including a bottom portion, a cover hingedly connected to a wall of the bottom portion, a removable tray adapted to be positioned in the bottom portion, a cup, means hingedly connecting the cup to the bottom wall of the tray whereby said cup 40 may be positioned flatly against said bottom wall or be positioned in substantially a hori-

zontal plane above the bottom wall, a second cup, means hingedly connecting said second cup to said bottom wall whereby said second cup may be disposed flatly against said bottom wall or positioned in a position beneath said first mentioned cup. 45

2. In a nurse's portable sterilizing kit, a tray, a cup, means hingedly connecting the cup to the bottom wall of the tray whereby said cup may be positioned flatly against said bottom wall or be positioned in substantially a horizontal plane above the bottom wall, a second cup, means hingedly connecting said second cup to said bottom wall whereby said second cup may be disposed flatly against said bottom wall or positioned in a position beneath said first mentioned cup. 50

3. In a nurse's portable sterilizing kit, a 60 casing including two sections hingedly connected together, a tray removably positioned in one of the sections, a cup providing an extension, a leg having one end portion hingedly connected to said extension, a plate 65 hingedly connecting the opposite end portion of said leg to the bottom wall of said tray, said leg and extension permitting said cup to be disposed flatly against said bottom wall and said leg functioning to support 70 said extension and cup in a horizontal plane with respect to the tray when said leg is positioned in a vertical plane, a second cup, a hinge structure providing connection between the second structure and the bottom 75 wall of the tray, said hinge structure permitting said second cup to be disposed between said first mentioned cup when said first mentioned cup is supported by said leg in said horizontal plane. 80

In testimony whereof I affix my signature.
JOHN L. ADAMS.
